CARBURETOR

Lloyd B. Grantham, Yonkers, N. Y., assignor to
 Phillips Petroleum Company, Bartlesville,
 Okla., a corporation of Delaware

Application April 18, 1933, Serial No. 666,767

18 Claims. (Cl. 123—119)

The present invention relates to charge forming devices or carburetors primarily intended for use in connection with internal combustion engines for motor vehicles and the primary object 5 of the invention is to provide a device of this character which acts, upon closing of the throttle, to automatically admit air only to the engine thus tending to cool the engine due to cessation of explosive charges entering the engine.

10 A further object of the invention is to provide a charge forming device wherein all flow of fuel is shut off and air only permitted to enter the engine when the throttle is fully closed and the vehicle is traveling under attained momentum thus resulting in a saving in fuel and preventing back firing on long down grades.

15 A further object of the invention is to provide a device which will supply fuel to the engine only when production of power is desired, and admits air only into the engine when power is shut off and the vehicle is traveling under attained momentum such as on down grades or coasting on the level.

20 A further object is to provide a carburetor of this character wherein when the throttle is fully closed and the vehicle traveling faster than idling speed due to attained momentum, air only will be admitted into the engine, and after the vehicle slows down to an idling rate of speed, an 25 idling supply of fuel is admitted to the engine automatically and without attention from the operator.

25 A further object of the invention is to provide an automatically operable charge forming device 30 acting upon suction of the engine when the throttle is fully closed, to shut off all fuel supply and permit air alone to enter the engine.

35 A further object resides in the novel arrangement whereby an idling supply of fuel is admitted to the engine when the vehicle speed 40 equals the idling speed of the engine.

40 A further object of the invention is to provide a device of this character in the form of an attachment adapted to be interposed between the 45 carburetor and intake manifold of an internal combustion engine and acting to automatically shut off the fuel supply and permit air only to enter the engine when the vehicle speed exceeds the idling speed of the engine.

50 Other objects and advantages of the invention will be apparent from the following detailed description, taken in connection with the accompanying drawings forming a part of this specification and in which drawings:—

55 Figure 1 is a central vertical section thru the

preferred form of carburetor with the parts in an idling position with the fuel supply valve slightly open to permit an idling supply of fuel to feed to the engine. This view shows the throttle control in a closed position with the throttle valve operating cams in their upward limit of movement.

Figure 2 is a central vertical section similar to Figure 1 but showing the throttle valve in its full open position imparting opening movement 10 to the fuel supply valve.

Figure 3 is a fragmentary section taken at a right angle to the showings in Figures 1 and 2 and showing the throttle valve opened by the suction of the engine such as when the speed of the vehicle exceeds the idling rate of speed of the engine.

Figure 4 is a horizontal section taken substantially on the line 4—4 of Figure 1.

Figure 5 is an enlarged fragmentary detail section showing the manner in which the removable metering nozzle may be placed in the jet or guide tube.

Figure 6 is a central vertical section thru a slightly modified form of carburetor and showing the parts in an idling condition with the throttle fully closed and permitting an idling supply of fuel mixture to enter the engine.

Figure 7 is a vertical section similar to Figure 6 but showing a full open throttle position of 30 the throttle valve and gasoline or fuel valve.

Figure 8 is a fragmentary vertical section taken at a right angle to the showings in Figures 6 and 7 and showing the parts in a coasting position with the throttle fully closed and the throttle valve raised by suction of the engine to shut off all fuel supply to the engine.

Figure 9 is a horizontal section on the line 9—9 of Figure 6.

Figure 10 is an enlarged detail sectional view 40 on the line 10—10 of Figure 6.

Figures 11 to 17 inclusive show a form of attachment adapted to be connected between the carburetor and intake manifold. Figure 11 shows a vertical section thru the attachment device 45 such as when the usual throttle at the carburetor is closed or at an idling position and the speed of the vehicle exceeds the idling speed of the engine thus permitting air alone to enter the engine.

Figure 12 is a sectional view similar to Figure 11 but showing the parts in a position when the throttle valve of the carburetor is fully open.

Figure 13 is a top plan view of the lower portion of the attachment and showing a fragmen-

tary portion of the air control valve broken away.

Figure 14 is a fragmentary sectional view on the line 14-14 of Figure 12.

Figure 15 is a vertical sectional view at a right angle to the showings in Figures 11 and 12 and showing the throttle in a closed or idling position and the fuel control valve of the attachment slightly raised by the suction of the

10 engine to permit passage of an idling supply of fuel to the engine.

Figure 16 is a view in side elevation of the attachment applied to an up-draft type of carburetor and with the parts in an idling position

15 as shown in Figure 15.

Figure 17 is a view in side elevation of the attachment shown applied to a down-draft type of carburetor.

Referring to the drawings in detail, and where-
20 in similar reference characters designate corre-
sponding parts thruout the several views, the
letter A may generally designate the form of
carburetor shown in Figures 1 to 5 inclusive, the
letter B the form of carburetor shown in Figures
25 6 to 10 inclusive, and the letter C the form of
attachment shown in Figures 11 to 17 inclusive.

Referring first to the form of carburetor A, the
5 numeral 5 designates the carburetor body which
is preferably of tubular formation being open
30 at its upper end and closed at its lower end by
a bottom wall 6 preferably provided with a
threaded opening 7 arranged axially of the tubular
body portion 5. Projecting laterally from
the lower end of the body portion 5 is the air
intake 8 in which is provided the usual choke
valve 9. Preferably formed integral with one side
of the body portion 5 at the lower end thereof is
a hollow extension 10 providing a float chamber
11 having a fuel supply inlet 12 controlled
40 by a float 13 serving to regulate the height of
fuel in the chamber 11. Forming communication
between the float chamber 11 and the opening
7 is a fuel supply duct 14 which may be formed
in the bottom wall 6. The upper open end of
45 the tubular body portion 5 is formed with the
usual attaching or coupling flange 15 which may
be suitably apertured for attachment of the car-
buretor to the intake manifold of an internal
combustion engine whereby the manifold has
50 communication with the upper end of the car-
buretor body.

Arranged to extend axially upwardly in the
55 tubular body portion 5 is a jet or guide tube 16
having an externally threaded lower end for
threading into the threaded opening 7 in the bot-
tom wall 6 whereby the lower end of the tube is
in communication with the fuel supply duct 14.
The lower end of the opening 7 may receive a
60 drain plug 17. The tube 16 is provided substan-
tially midway its height with an air cone 18
and slightly above this cone with a cone-shaped
deflector 19 having its apex directed downwardly.
The tube 16 is provided with air inlet openings
65 20 arranged below the cone 18, and outlet open-
ings 21 arranged between the cones 18 and 19.

The tubular body portion 5 is provided above
the open upper end of the tube 16 with an in-
70 ternal flange 22 which is beveled at its inner
edge to provide a circular opening arranged ax-
ially above the tube 16.

Reciprocally guided in the upper portion of
the tube 16 is a throttle valve including a disc
23 vertically movable thru the opening formed
75 by the internal flange 22, and a depending plung-
er portion 24 slidably fitting in the tube 16. This

throttle valve disc 23 has its circumferential edge
beveled and is of a diameter to provide an an-
nular passageway about the disc when the disc
aligns with the flange 22 as in Figure 1. This
annular passageway formed by providing a 5
clearance between the disc 23 and internal flange
22 allows for an idling supply of fuel to pass the
disc when the disc is in an idling position as in
Figure 1.

Encircling the upper portion of the tube 16 10
with its lower end engaging the cone 19 and its
upper end engaging the disc 23 is a coil spring
25 serving to normally return the throttle valve
disc 23 to its idling position in the flange 22.
This coil spring 25 is of such length that when
fully expanded as in Figures 1 and 3, the disc 23
15 is supported by the spring in an idling position
as in Figure 1.

Journalized in the upper portion of the tubular
body 5 to extend diametrically thru the tubular 20
body in spaced relation above the flange 22 is a
control shaft 26 having fixedly mounted thereon
a pair of throttle valve cams 27 adapted to en-
gage the upper edge of the disc 23 and force
the disc downwardly from an idling position as 25
in Figure 1 to an open throttle position as in
Figure 2. The control shaft 26 is provided at
one end with an operating lever 28 which may be
connected in any suitable manner with a control
rod operated by a hand throttle lever and an 30
accelerator pedal as in usual practice. The con-
trol shaft 26 is preferably rotatable thru 90° of
rotation by the lever 28, with 45° of the move-
ment serving to move the throttle valve from an
idling to a full open position. When the throttle 35
lever 28 is in a full closed throttle position, the
cams 27 are moved out of contact with the upper
limit of movement of the disc 23. When the
throttle is opened, the throttle valve is lowered
against the tension of the spring 25 and the 40
force of the air being drawn thru the air intake
tube.

The guide tube 16, immediately below the air
openings 20 is internally threaded as at 29 to re-
ceive a removable externally threaded nozzle 30 45
having a constricted upper portion providing a
conical valve seat 31 as shown more clearly in
Figure 5. Reciprocally guided in the lower portion
of guide tube 16 is a fuel control valve 32
having a conical seat portion adapted to engage 50
upon the conical valve seat 31 and a stem portion
33 which projects upwardly thru the nozzle 30
with its upper end adapted to engage the lower
end of the plunger 24. The control valve 32 has
suitable ports therethru to permit passage of gaso- 55
line. The lower end of the tube 16 is internally
threaded as at 34 for receiving a tubular stop
plug 35. Arranged in the tube 16 between the
valve 32 and plug 35 is an expansion coil spring
36 acting to normally seat the valve and shut off 60
escape of fuel thru the nozzle 30. Adjustment
of the plug 35 will vary the closing tension of the
spring 36 upon the valve 32.

Journalized in the upper portion of the tubular
carburetor body portion 5 in right angular re- 65
lation to the control shaft 26 and with its inner
end disposed closely below the control shaft, is an
idling adjustment rod 37 provided exteriorly of
the tubular body with a knurled rotating knob 38.
Provided on the inner end of the rod 37 is a cam 70
or eccentric 39 which acts upon a head 40 provided
on the upper end of a guide pin 41 having move-
ment into a pocket 42 formed in the plunger
portion 24 of the throttle valve and opening at
the upper side of the disc 23. The pocket 42 75

is closed at its lower end. Encircling the guide pin 41 with its lower end engaging the base of the pocket 42 and its upper end engaging the head 40 is an idling adjusting coil spring 43 for retaining the throttle valve disc 23 in an idling position when the throttle is fully closed. The tension of the idling spring 43 may be varied by means of the cam 39 on the adjusting rod 37. The tension on the spring 43 is adjusted so as to 10 slightly overcome the tension of the fuel valve spring 36 and the air suction thru the carburetor whereby the throttle disc 23 is returned to an idling position and slightly unseat the valve 32 when the throttle is fully closed.

15 In operation of the carburetor A, when the engine is idling with the throttle fully closed, the carburetor will be in a condition as shown in Figure 1 with the fuel control valve 32 slightly opened permitting an idling supply of fuel to escape at the nozzle 30 and mix with the air entering the intake 8 and this mixture permitted to pass thru the annular passageway about the throttle disc 23 into the intake manifold of the engine. Upon opening of the throttle, the cams 20 25 27 engage the disc 23 and force the disc downwardly against the tension of the spring 25 and causing opening of the fuel control valve 32 by the plunger 24 forcing the stem 33 downwardly. Figure 2 shows a full open throttle position of the carburetor. Upon coming to a down grade or when the vehicle is traveling under attained 30 momentum from high speed, the operator fully closes the throttle allowing the throttle valve to be raised by the spring 25, and if the speed of the vehicle exceeds the idling speed of the engine, the throttle valve will be raised by suction to its full opening position as in Figure 3. This raising of the throttle valve relieves all pressure on the fuel control valve 32 which is immediately closed by the spring 36 thus shutting off all fuel supply to the carburetor, and allowing air only to be drawn into the engine. When the coasting speed of the vehicle is lowered to the idling speed of the engine, suction thru the carburetor will be greatly reduced and allows the throttle valve to be returned by the idling spring 43 to an idling position and slightly opening the fuel valve 32. The cycle of operation of the carburetor is of course obtained with the gearing of 40 the vehicle in mesh at all times.

50 Referring particularly to the Venturi effect formed by the cones 18 and 19, the cone 18 will direct a considerable amount of air thru the air openings 20 to the outlet of the nozzle 30 so that the velocity of air at this point will be very high thus insuring perfect atomization of the fuel which is then directed outwardly by the deflector cone 19 for mixing with additional air at the wall of the tubular body portion 5.

60 The removable nozzle 30 is designed to give the proper gasoline flow at any given throttle opening and will be available in various inside diameters for use upon different types of engines.

65 Referring now to the form of carburetor B shown in Figures 6 to 10 inclusive, the carburetor is formed with a tubular body portion 5' closed at its lower end by a bottom wall 6' formed with a threaded opening 7' arranged axially of the tubular body portion. Projecting from the lower end of the body portion 5' is an air intake 8' in which is provided the usual choke valve 9'. Formed integral with the lower portion of the body portion 5' is an extension 10' providing a float chamber 11' having a fuel supply inlet 12', 70 controlled by the float 13'. A duct 14' provides

communication between the float chamber and the threaded opening 7'. The upper open end of the tubular body portion 5' is provided with the usual attaching flange 15' for attachment of the carburetor to the intake manifold of an internal combustion engine.

75 Arranged axially within the lower portion of the tubular body portion 5' is a jet or guide tube 16' having an externally threaded lower end for threading into the opening 7' whereby the lower open end of the tube communicates with the duct 14'. The lower end of the opening 7' may be closed by a suitable drain plug 17'. The tube 16' is provided substantially midway its height with an air cone 18' and directly above this cone 15 with a deflector cone 19'. The tube 16' is provided below the apex of the cone 18' with air inlet openings 20', and between the cones with outlet openings 21'.

80 The tubular body portion 5' is provided above the cone 19' with an internal annular flange 22' providing an upwardly flaring valve seat 45 arranged concentric to the tube 16'.

85 Slidably guided upon the upper end portion of the guide tube 16' is a throttle valve embodying 25 a disc valve 46 for engaging upon the seat 45 and a sleeve portion 47 slidably fitting over the guide 16'. This sleeve portion 47 projects above the disc 46 for a purpose to be subsequently described.

90 Journalized in the upper portion of the tubular body portion 5' to extend diametrically therethru above the internal flange 22' is a throttle control shaft 48 provided with a pair of spaced apart cams 49 which are adapted to engage the upper surface of the disc 46 and control upward movement of the disc by the suction of the engine. One end of the shaft 48 is provided with a throttle lever 50 so connected to an accelerator or hand throttle as to impart 90° of rotation 40 to the shaft 48.

95 Idling adjustment means is provided for controlling raising of the disc 46 when the engine is idling, and this means embodies an idling coil spring 51 which encircles the upper end of the 45 throttle valve sleeve 47 with its lower end bearing upon the disc 46. Fitting upon the upper end of spring 51 is a flanged washer 52 adapted to work between the cams 49. Threaded thru the body portion 5' above the flange 22' in right 50 angular relation to the shaft 48 is an idling adjustment rod 53 formed at its inner end with an annular groove 54 and at its outer end with an operating knob 55. Pivotally mounted above the rod 53 as between suitable lugs 56 is a bell crank 55 lever having the free end of its arm 57 engaging in the annular groove 54, and its arm 58 extending downwardly and inwardly and forked at its free end providing fingers 59 adapted to bear upon the flanged washer 52. By observing Figure 6 it will be seen that when the rod 53 is threaded outwardly, the fingers 59 will move downwardly to increase the tension on the spring 51, and when the rod is threaded inwardly the fingers will be raised to reduce tension on the 65 spring 51. By adjusting the tension on the spring 51, the rate of idling speed may be controlled by varying the degree of tension required to raise the throttle valve when the throttle is fully closed. It may here be well to state that 70 when the cams 49 are in the closed throttle position as in Figure 1, the cams do not force the disc 46 upon the seat 45 but provide a slight clearance permitting slight raising of the disc. When the engine is idling, with the throttle fully 75

- closed, the incoming air raises the disc 46 against the tension of the spring 51, and the tension of this spring, adjusted by the rod 53, regulates the rate of idling speed.
- 5 The guide tube 16' is internally screw threaded at a point just below the air openings 21' for threaded reception of a tubular metering nozzle 60 provided at its upper end with a conical valve seat 61.
- 10 Reciprocally movable in the upper portion of the guide sleeve 16' is a fuel control valve embodying a cylindrical stem portion 62 slidably fitting in the tube 16' and provided at its upper end with a cylindrical head portion 63 slidably fitting in the sleeve portion 47 of the throttle valve. The lower end of the stem portion 62 is reduced in diameter and provided at its extremity with a tapering seat 64 for engaging upon the seat 61. The stem portion 62 is provided with an axially disposed idling fuel passageway 65 which extends upwardly into the head portion 63 and communicates with the transverse passageway 66 which opens into an annular passageway 67 formed circumferentially of the head portion. The sleeve portion 47 of the throttle valve is provided above the disc 46 with suitable openings 68 which provide escape openings for an idling supply of fuel when the throttle is fully closed as in Figure 6.
- 15 30 The control shaft 48 is provided between the cams 49 with a fuel valve control cam 70 adapted to engage the upper end of the head 63 for closing the fuel control valve in unison with closing of the throttle valve. Encircling the head portion 63 of the fuel control valve is an expansion coil spring 71 having its lower end bearing upon the upper end of the sleeve 47 and its upper end acting against an annular flange 72 provided on the head 63. This spring 71 acts as a lift spring normally urging the head 63 into engagement with the cam 70.
- 20 35 The cams 49 and 70 bear a specific relation to one another whereby when the control shaft 48 is rotated to a full closed throttle position, the disc 46 will be lowered by the cams 49 and the fuel control valve will be lowered by the cam 70 so as to prevent escape of fuel thru the outlet openings 21' into the chamber below the flange 22'.
- 40 45 50 Referring now to the manner of operation of the carburetor B, with the engine running and the throttle fully closed, the carburetor will be in a position as shown in Figure 6. In this idling position, the seat 64 of the control valve stem 62 is engaging upon the seat 61 of the nozzle 60 and the disc 46 of the throttle valve is slightly raised by the suction of the engine against the tension of the idling spring 51 and allowing a small amount of air to pass about the disc. With the fuel control valve fully seated by the cam 70, raising of the disc 46 by suction of the engine aligns the openings 68 in the sleeve 47 with the annular passageway 67 allowing an idling supply of fuel to be drawn upwardly thru the idling fuel passageway 65 for mixing with the air drawn past the slightly raised disc 46. Upon opening of the throttle, the cams 49 swing thru 90° of movement from a closed to an open throttle position and this opening of the throttle moves the low side of the cam 70 against the control valve head 63 allowing opening of the control valve and permitting escape of fuel thru the outlet openings 21'. The suction of the engine raises the throttle disc 46, and Figure 7 shows the carburetor in a full open throttle position. When coasting down grades,
- 55 60 65 70 75 or when the vehicle is traveling under attained momentum, the operator fully closes the throttle and rotates the shaft 48 so that the cams 49 and 70 are in a position as in Figure 8. In this position, the fuel control valve is fully closed upon the seat 61 and so long as the speed of the vehicle exceeds the idling speed of the engine, the disc 46 is raised by suction of the engine and disaligns the openings 68 with the idling fuel passageway 67 so that all fuel supply is shut off and only air is permitted to enter the engine. When the speed of the vehicle is reduced to idling speed of the engine, the suction of the engine is greatly reduced allowing the idling spring 51 to lower the disc 46 to an idling position so that the openings 68 again align with the annular idling fuel passageway 67 whereupon combustion is again resumed at an idling rate of speed. With the cams 49 and 70 in a position as in Figure 8, the carburetor will be automatic in its operation to allow only air to enter the engine when the vehicle speed exceeds idling speed of the engine, and automatically supply an idling quantity of fuel to the engine when the speed of the vehicle is reduced to the idling speed of the engine.
- 80 85 90 Referring now to the form of carburetor attachment C shown in Figures 11 to 17 inclusive, this attachment is adapted for connection between the usual carburetor and the intake manifold thereof and connected for operation upon operation of the usual throttle of the carburetor. The device or attachment C is preferably formed in two sections 74 and 75 which, for the purpose of explanation may be termed upper and lower sections respectively. The sections 74 and 75 may be secured together by suitable assembling bolts 76. Referring particularly to Figures 11 to 16 inclusive, showing the device applied to an up draft type of carburetor generally designated by the letter D, the upper end of the section 74 is formed with threaded sockets for receiving cap screws 77 whereby the device may be connected to the intake manifold 78 of an internal combustion engine. The lower side of the section 75 is provided with threaded sockets for receiving cap screws 79 for connection of the carburetor to the device.
- 95 100 The section 74 is provided with a chamber 80 communicating with the intake manifold 78, while the lower section 75 is formed with a circular chamber 81 of a diameter smaller than that of the chamber 80. The chamber 81 has communication with the charge outlet tube 82 of the carburetor whereby the fuel charge is permitted to pass thru the device C to the intake manifold.
- 105 Secured at its lower end as by suitable arms 83 to the lower end of the section 75 and extending axially thru the chamber 81 into the chamber 80 is a guide stem or rod 84 providing a guide for an air control valve 85 and a fuel control valve 86.
- 110 The section 75 is formed with an annular channel which, when assembled with the section 74 provides an annular passageway 87. Communicating with the annular air passageway 87 is a suitable number of air intake passages 88 which extend in upwardly and inwardly relation toward the axis of the chamber 80 and open upon an annular valve seating face 89. These air intake passages 88 are closed by the air control valve 85 embodying a tubular hub portion 90 guided on the stem 84 and connected by arms 91 to an annular valve ring 92 having a beveled seat adapted to engage upon the seating face 89 when the valve is lowered. Thus it will be seen that the valve 75

85 serves to control passage of air into the chamber 80 thru the intake openings 88.

The fuel control valve 86 is in the form of a solid disc valve slidably guided on the lower portion 5 of the stem 84 and adapted to engage upon an annular valve seat 93 at the lower end of the chamber 81 to control communication between this chamber and the carburetor tube 82.

Secured in any preferred manner in the chamber 81 is a support 94 of open construction so as not to obstruct passage of fuel therethru and this support is provided with depending lugs 95 for pivotal mounting of a pair of valve operating levers 96.

15 These levers 96 are pivoted intermediate their ends as upon the pivot pins 97 and at one end are adapted to freely engage the valve disc 86. The opposite end of the levers 96 are forked as shown more clearly in Figure 14 and the forked ends 20 of the levers have pin portions adapted to engage in the annular groove of a collar 98 provided on the lower end of the tubular hub 90. By observing Figure 11, it will be seen that upon raising of the control valve 85, the operating levers 96 will 25 act to force the fuel valve 86 upon the seat 93. When the valve 85 is engaging upon the seat 89 as in Figure 12, the levers 96 will be in a position permitting raising of the valve disc 86 by the suction created by the engine. It may here be 30 well to note that when the valve disc 86 is engaging upon the seat 93, that communication is shut off between the carburetor and intake manifold so that no fuel mixture enters the intake manifold.

35 An idling adjusting means is provided for retaining the air control valve 85 seated under idling speed of the engine and this means embodies an idling spring 99 encircling the upper end of the guide stem 84 and bearing upon the 40 tubular hub 90 of the control valve. Extending diametrically thru the chamber 80 and rotatably mounted in the section 74 is an idling adjustment rod 100 provided at its outer end with a suitable 45 rotating knob 101. The intermediate portion of the rod 100 is provided with a cam or eccentric 102 adapted to engage with a cap plate 103 fitting over the upper end of the idling spring 99. Rotation of the rod 100 will vary the tension on the spring 99 whereby the air control valve 85 50 may be held seated when the throttle is closed or in an idling position.

55 The carburetor is provided with the usual throttle valve 104 arranged in the tube 82 and mounted on the shaft 105 projecting exteriorly of the tube 82.

Rotatably journaled in the attachment section 60 74 to extend diametrically thru the chamber 80 in right angular relation to the idling adjustment rod 100, is a cam shaft 106 provided with a pair of cams 107 connected by a bridge piece 108 permitting rotation of the cam shaft without interfering with the rod 100. These cams 107 are adapted to engage an annular flange 90' 65 formed about the upper end portion of the tubular hub 90 of the air control valve 85.

70 A coupling means is provided for controlling operation of the shaft 106 upon opening and closing of the throttle valve 104 and this means acts to permit automatic operation of the attachment to admit air only to the engine when the vehicle speed exceeds the idling speed of the engine when the throttle is closed, and also to positively hold the air control valve 85 seated when the throttle is opened. Secured to the outer end of the throttle valve shaft 105 is a control disc 109 to which

is connected a suitable throttle control rod 110 which may be connected in the usual manner to a foot accelerator and a hand throttle lever. Pivotally mounted at one end as upon a suitable bracket 111 clamped about the charge outlet tube 82 of the carburetor is an operating lever 112 which is provided closely adjacent its pivoted end with a segmental-shaped projection 113 for bearing engagement upon the periphery of the disc 109 and adapted to engage in a segmental-shaped 10 depression 114 formed in the periphery of the disc. Pivotally connected at one end to the free end of the lever 112 is a link 115, the opposite end of which is pivotally connected to a crank arm 116 fixed to the outer end of the cam shaft 15 106. A tensioning spring 117 is connected between the lever 112 and the body portion of the attachment and acts to normally urge the lever toward the control disc 109 so that the projection 113 contacts the disc at all times. As shown 20 in Figure 16, when a pull is exerted on the throttle rod 110 in the direction of the arrow to open the throttle, the projection 113 will ride out of the depression 114 and so swing the lever 112 as to impart rotation to the cam shaft 106. 25

The carburetor D is provided with an air cleaner E embodying a carburetor section 118 and an attachment section 119. The main or carburetor section 118 is provided with a tube 120 which connects with the main air intake 121 of the carburetor, while the minor or attachment section 119 of the cleaner is connected by an air tube 122 with the annular air passageway 87 of the attachment. This providing of separate air cleaner sections for the carburetor and the attachment is to prevent likelihood of the fuel mixture being drawn from the carburetor thru the main air intake 121 and then thru the air intake tube 122 into the engine when the parts are in a condition as shown in Figure 11. With the 40 double sectioned air cleaner, no back suction will be created in the tube 120 when a suction is created in the air tube 122.

Figure 17 shows the attachment C in an inverted position of use for connection between a 45 down draft type of carburetor F, and its manifold.

Referring now to the operation of the attachment C, Figure 11 shows a coasting condition when the throttle valve 104 is fully closed and 50 the speed of the vehicle exceeds the idling speed of the engine. In this position, air entering the air intake passages 88 due to the suction of the engine, raises the air control valve 85 so that the levers 96 operate to close the fuel valve 86 thus 55 shutting off all fuel supply and permitting only air to enter the engine. When the throttle valve 104 is fully opened as in Figure 12, the cams 107 hold the air valve 85 upon its seat 89 and so position the levers 96 as to permit the fuel disc 86 to 60 be free to raise by the suction of the engine. With the throttle closed, when the vehicle speed is lowered to the idling speed of the engine so that the suction created by the engine is reduced, the idling spring 99 will seat the air valve 85 so 65 that the fuel valve 86 may be raised slightly to permit an idling supply of fuel to feed to the engine.

The coupling means between the throttle valve shaft 105 and cam shaft 106 is such as to rotate 70 the cams 107 to a position engaging the air valve 85 upon a slight degree of opening movement of the throttle valve so that no air is permitted to enter thru the passages 88 and mix with the fuel charge during normal operation of the engine. 75

Thus it will be seen that in all forms of the invention that an arrangement is provided whereby all flow of fuel is automatically shut off when the throttle is closed and the speed of the vehicle exceeds the idling rate of speed of the engine. It will also be noted that the device is automatic in its operation to supply an idling fuel supply to the engine when the vehicle speed is reduced to the idling rate of speed of the engine.

10 Changes in detail may be made to the forms of invention herein shown and described, without departing from the spirit of the invention or the scope of the following claims.

I claim:

15 1. In a charge forming device for internal combustion engines of motor vehicles, a fuel control valve, a throttle valve member adapted to be opened by suction of the engine, movement controlling means for the throttle valve member, 20 means for automatically closing the fuel control valve upon opening of the valve member by suction of the engine, and means for normally retaining the throttle valve member in an idling position for supplying an idling quantity of fuel to 25 the engine when the vehicle speed equals the idling speed of the engine.

2. In a charge forming device for internal combustion engines of motor vehicles, a fuel control valve, a throttle valve member adapted to be 30 opened by suction of the engine when the vehicle speeds exceeds idling speed of the engine, cam means for controlling movement of the valve member, means automatically closing the fuel control valve upon opening of the throttle valve 35 member by suction of the engine, and means normally returning the throttle valve member to an idling position to permit an idling supply of fuel to feed to the engine.

3. In a charge forming device for internal combustion engines of motor vehicles, fuel feeding control means, a throttle valve member adapted to be 40 opened by suction of the engine, throttle control means for controlling movement of the valve member for production of power, and means 45 for controlling the fuel feeding control means upon movement of the throttle valve member to shut off feeding of fuel when the valve member is opened by the engine suction and to permit feeding of fuel when the valve member is moved by 50 the throttle control means.

4. In a carburetor having a fuel inlet and an air inlet, a throttle valve for controlling feeding of the fuel mixture to the engine and adapted to be 55 opened by suction of the engine, cam means for controlling the mixture feeding position of the throttle valve, means normally returning the throttle valve to an idling position, and a fuel control valve associated with the throttle valve for shutting off the fuel supply upon opening 60 of the throttle valve by engine suction.

5. In a carburetor embodying a tubular casing, a jet tube in the casing, a fuel control valve 65 slideable in the jet tube, a throttle valve slideably associated with the jet tube and adapted to be opened by suction of the engine, cam means for controlling charge feeding positions of the throttle valve, adjustable idling return means for the 70 throttle valve, and cooperative means between the valves for feeding of an idling supply of fuel when the throttle valve is in an idling position.

6. In a carburetor embodying a hollow body portion for attachment to an intake manifold, a jet tube extending into the hollow body portion and having a fuel inlet, a fuel control valve 75 reciprocally guided in the jet tube, a throttle valve

slidably guided on the jet tube, said throttle valve adapted to be opened by suction of the engine, cam means acting upon the throttle valve to control the charge feeding position of the valve, adjustable idling return means for the throttle valve, and means permitting feeding of an idling supply of fuel when the throttle valve is in an idling position, said idling fuel supply being entirely shut off upon opening of the throttle valve by the engine suction.

7. A carburetor comprising in combination, a tubular body portion for attachment to an intake manifold, a guide tube in the body portion and having a fuel inlet at its lower end, a fuel valve guided in the lower portion of the tube for controlling escape of fuel thru the intermediate portion of the tube into the body portion, a throttle valve guided in the upper portion of the tube for opening the fuel valve upon a downward throttle opening movement of the throttle valve, and 20 control means for opening the throttle valve with a downward movement, said throttle valve adapted to be raised from an idling position by suction of the engine and permit full closing of the fuel valve.

8. A carburetor comprising in combination, a tubular body portion for attachment to an intake manifold, a guide tube in the body portion and having a fuel inlet at its lower end, a fuel valve guided in the lower portion of the tube for controlling escape of fuel thru the intermediate portion of the tube into the body portion, a throttle valve guided in the upper portion of the tube for opening the fuel valve upon a downward throttle opening movement of the throttle valve, throttle control cams for opening the throttle valve with a downward movement of the valve, said throttle valve adapted to be raised from an idling position by suction of the engine and permit full closing of the fuel valve, an idling 40 spring normally returning the throttle valve to an idling position to cause slight opening of the fuel valve, and means for adjusting the tension of the idling spring.

9. In a carburetor, a tubular body portion for 45 attachment to an intake manifold, a guide tube mounted axially in the body portion and having a fuel inlet at its lower end, a throttle valve guided in the upper portion of the tube, means normally raising the valve to an idling position, 50 a fuel valve guided in the lower portion of the tube for controlling escape of fuel thru the intermediate portion of the tube into the body portion, spring means normally urging the fuel valve upwardly to a closed position, throttle control 55 means for lowering the throttle valve and causing opening of the fuel valve, and adjustable idling tensioning means for the throttle valve permitting raising of the throttle valve by the engine suction when the engine exceeds an idling rate 60 of speed with said throttle control means in a closed position.

10. A carburetor comprising a tubular body portion having an internal ring flange, a jet tube mounted in the body portion axially of the ring 65 flange and having fuel escape openings intermediate its ends, a throttle valve embodying a disc movable thru the ring flange and a plunger portion guided in the upper end of the jet tube, yieldable closing means normally urging the 70 throttle valve upwardly to an idling position with the disc aligning within the ring flange, throttle control means for opening the throttle valve against the action of the closing means, a fuel valve guided in the jet tube below the fuel escape 75

openings, spring means normally urging the fuel valve upwardly to a closed position, a stem on the fuel valve engageable by said plunger portion for opening the fuel valve upon lowering of the 5 throttle valve, said throttle valve to be raised above the ring flange by the suction of the engine and permit full closing of the fuel valve, and idling adjustment means for returning the 10 throttle valve to an idling position with the fuel valve slightly opened when the throttle control means is closed and the engine is running at an idling speed.

11. A carburetor comprising a tubular body portion having an internal ring flange, a jet tube 15 mounted in the body portion axially of the ring flange and having fuel escape openings intermediate its ends, a throttle valve embodying a disc movable thru the ring flange and a plunger portion guided in the jet tube above the fuel 20 escape openings, a coil spring supporting the throttle valve in an idling position with the disc aligning within the ring flange, throttle opening cams engageable with the disc for opening the throttle with a downward movement, a fuel valve 25 guided in the jet tube below the fuel escape openings and having a stem engageable with said plunger portion for opening the fuel valve upon lowering of the throttle valve, spring means normally urging the fuel valve upwardly to a closed 30 position, said throttle valve to be raised by suction of the engine from an idling position with the disc aligning within the ring flange, an idling spring acting against the upper side of the throttle valve, and means for adjusting the tension of the idling spring for causing slight opening 35 of the fuel valve when the throttle valve is in an idling position with the throttle control means closed.

12. A carburetor comprising a tubular body portion having an internal ring flange, a jet tube 40 mounted axially in the body portion and having fuel escape openings intermediate its ends, a throttle valve embodying a disc movable with clearance thru the ring flange and a plunger portion guided in the upper end of the jet tube, a 45 coil spring yieldably supporting the throttle valve with the disc aligning within the ring flange, a control shaft journaled in the body portion above the ring flange, cams mounted on the control shaft and engageable with the throttle valve disc for opening the valve with a downward movement, said cams when in a raised closed position permitting the throttle valve to be raised by the suction of the engine, said plunger portion of the 50 throttle valve having an upwardly opening pocket, an idling coil spring arranged in said pocket, a guide pin extending into the upper end of the idling spring and having a head at its upper end forming an abutment for the upper 55 end of the idling spring, an idling adjustment rod journaled in the body portion above the ring flange, a cam on the inner end of the adjustment rod and engageable with the head of the guide pin for adjusting tension on the idling 60 spring, and a spring seated fuel valve guided in the jet tube below the fuel escape openings therein and adapted to be closed upon upward movement of the throttle valve from an idling position.

70 13. A carburetor comprising a tubular body portion having an internal ring flange adjacent its upper end and air and fuel inlets adjacent its lower end, a jet tube mounted axially in the tubular body portion and communicating at its 75 lower end with the fuel opening, said jet tube

being provided intermediate its ends with air inlet openings and above these openings with fuel outlet openings, an air collector cone encircling the jet tube between the openings, a deflector cone encircling the jet tube above the fuel outlet openings, a nozzle in the jet tube below the air inlet openings, a fuel control valve for controlling escape of fuel thru said nozzle, spring means normally closing the fuel valve, a throttle valve guided in the upper end of the jet tube 10 embodying a plunger portion closing the upper end of the tube and a disc portion movable thru the ring flange, and control means for the throttle valve, said throttle valve when opened to cause opening movement to be imparted to the 15 fuel control valve.

14. A carburetor comprising a tubular body portion for attachment to an intake manifold, a jet tube mounted axially in the body portion and having fuel escape openings intermediate its 20 ends, a tubular nozzle in the tube below said openings, a fuel valve guided in the upper end of the jet tube for controlling escape of fuel thru said nozzle, a throttle valve slidably guided on the upper end of the jet tube and adapted to be 25 opened by suction of the engine, and throttle control means for controlling opening movement of the throttle valve.

15. A carburetor comprising a tubular body portion for attachment to an intake manifold, 30 a jet tube mounted axially in the body portion and having fuel escape openings intermediate its ends, a tubular nozzle in the tube below said openings, a fuel valve guided in the upper end of the jet tube for controlling escape of fuel thru 35 said nozzle, a throttle valve slidably guided on the upper end of the jet tube and adapted to be opened by suction of the engine, throttle control means for controlling opening movement of the throttle valve, and means operable upon closing 40 of the throttle control means for admitting an idling supply of fuel to the engine.

16. A carburetor comprising a tubular body portion for attachment to an intake manifold, a jet tube mounted axially in the body portion and having fuel escape openings intermediate its ends, 45 a tubular nozzle in the tube below said openings, a fuel valve guided in the upper end of the jet tube for controlling escape of fuel thru said nozzle, a throttle valve slidably guided on the upper 50 end of the jet tube and adapted to be opened by suction of the engine, throttle control means for controlling opening movement of the throttle valve, and means operable upon closing of the throttle control means for by-passing an idling 55 supply of fuel when the engine is running at idling speed and shutting off the idling supply of fuel when the engine speed exceeds the idling rate of speed of the engine.

17. A carburetor comprising a tubular body portion for attachment to an intake manifold, a jet tube mounted axially in the body portion and having fuel escape openings intermediate its ends, 60 a tubular nozzle in the tube below said openings, a fuel valve guided in the upper end of the jet tube and having a stem portion for controlling escape of fuel thru the nozzle, a throttle valve 65 slidably guided on the upper end of the jet tube and adapted to be opened by suction of the engine, an idling tensioning spring normally closing the throttle valve, tension adjusting means for said spring, spring means acting to normally open the fuel valve, throttle control means for controlling opening movement of the throttle valve, means associated with the throttle control means 70 75

for closing the fuel valve, and by-pass means permitting feeding of an idling fuel supply upon closing of the fuel valve.

- 5 18. A carburetor comprising a tubular body portion for attachment to an intake manifold, a jet tube mounted axially in the body portion and having fuel escape openings intermediate its ends, a tubular nozzle in the tube below said openings, a fuel valve embodying a stem portion guided in the upper end of the jet tube and a head portion at the upper end of the stem, said stem portion having an idling fuel passageway therethru opening into an annular idling fuel passageway about the head portion, said stem portion to seat upon the nozzle for controlling escape of fuel thru said fuel escape openings, a throttle valve embodying a sleeve portion slidably guided on the

upper end of the jet tube and having idling fuel escape openings for registering with said annular idling fuel passageway, said throttle valve adapted to be opened by suction of the engine, an idling spring acting to normally close the throttle valve, a spring means acting to normally open the fuel valve, a control shaft journaled transversely of the upper portion of the tubular body portion, cams on the control shaft for controlling opening movement of the throttle valve, and a cam on the 10 control shaft for closing the fuel valve and permitting escape of an idling supply of fuel thru the idling fuel escape openings in the throttle valve sleeve upon movement of the throttle valve to an idling position.

15 LLOYD B. GRANTHAM.
